No. 37,425.

Patented May 9, 1905.

UNITED STATES PATENT OFFICE.

JOHN CLULEE, OF WALLINGFORD, CONNECTICUT, ASSIGNOR TO INTERNATIONAL SILVER COMPANY, OF MERIDEN, CONNECTICUT, A CORPORATION OF NEW JERSEY.

DESIGN FOR A HANDLE FOR SPOONS, FORKS, OR SIMILAR ARTICLES.

SPECIFICATION forming part of Design No. 37,425, dated May 9, 1905.

Application filed April 1, 1905. Serial No. 253,371. Term of patent 7 years.

To all whom it may concern:

Be it known that I, JOHN CLULEE, a citizen of the United States, residing at Wallingford, in the county of New Haven and State 5 of Connecticut, have invented a new, original, and ornamental Design for a Handle for Spoons, Forks, or Similar Articles; and I do hereby declare the accompanying drawing to be a full, clear, and exact illustration of the 10 same, and which said drawing constitutes part

of this specification, and represents a face view of a handle for a spoon, fork, or similar article embodying my design.

I claim—

The ornamental design for a handle for a 15 spoon, fork or similar article, as shown.

JOHN CLULEE.
